UNITED STATES PATENT OFFICE.

ABRAHAM J. EISENBERG, OF CHICAGO, ILLINOIS.

SANITARY SHAVING CUP.

Application filed February 11, 1927. Serial No. 167,516.

This invention relates to shaving cups and more particularly to cups made from paper or the like and adapted to be used only for one shaving.

5 The principal object of the invention is to provide a shaving cup of this nature having a brush therein, so arranged that the cup cannot be used without breaking its seal, and after its use the cup and brush can be thrown 10 away.

Another object of the invention is to provide a device of this character having a perforated body with means to cut along the perforations in order to break the seal when 15 the cup is to be used.

Other objects will appear as the disclosure progresses. The drawings are intended merely to indicate a possible embodiment of the invention. It is obvious that the actual 20 needs of manufacture may necessitate certain mechanical changes. It is therefore not intended to limit the invention to the embodiment illustrated, but rather to define such limits in the appended claim.

25 For a more general understanding of the invention, attention is now called to the drawings in which a preferred embodiment is shown illustrated.

Figure 1 is a front elevation of the shaving cup.

30 Fig. 2 is a similar view as Fig. 1, but with the sealing band removed.

Fig. 3 is a section on line 3—3 of Fig. 1.

Fig. 4 is a section on line 4—4 of Fig. 3.

35 Fig. 5 is a perspective view of the lower cup portion.

Fig. 6 is a perspective view of the upper part of the cup.

Fig. 7 is a view of the wire snare or loop.

40 Referring to the drawing in detail, in which like reference characters denote like parts throughout the specification, numeral 1 designates the cup preferably made from paper or the like and cylindrical in shape and having a top 2 and bottom 3 which are firmly held in place by the wall of said cup.

45 Within the cup is a shaving brush 4 held in place by a wire loop 5. The loop is S-shaped as shown in Fig. 7. For supporting the brush, the brush bristles 6 are placed in one portion of the loop and then the wire is twisted around itself and thus firmly gripping the bristles. The shoulder formed by

the brush handle 7 will prevent the brush from slipping downward through the loop. The free end of the wire loop is then passed 55 through the opening 8 and bent downward as shown at 9.

On line with the opening 8 extending all the way around the cup is a line of perforations 10, and pasted to the cup body on the same level is a band 11. As will be seen in Fig. 1, the band has a widened portion 12 so as to cover the area formed by the opening 8 and part of the support 5, leaving the free end 9 exposed so it can be taken hold of.

46 At the bottom of the cup is shown a capsule 13 holding a supply of powdered soap for one shaving.

50 In order to use the cup for a shave, the end of the wire is bent upwardly, as shown in dotted lines in Fig. 3, and the wire holding the brush moved along the perforations. This will cause the perforations to be cut as if with a knife by the action of the wire between the brush and the bent down wire portion, and thus cut away the upper portion 55 of the cup leaving access to the brush and using the lower portion as a shaving cup.

55 The following is the method used for assembling and sealing the cup.

60 The body of the cup is perforated as at 10 and the hole 8 cut in the side. The brush carrier 5 looped around the brush 4 is passed through the hole, the end bent down and the band seal 11 pasted along the perforations. The capsule 13 is then placed in the box and the top cover 2 put in place. The cup is 65 next inverted and dipped in a bath of paraffine up to the line 14, thereby providing a seal which cannot be broken without the fact being apparent.

70 Having thus described my invention, what I desire to secure by Letters Patent is:

75 In a sanitary shaving cup of the class described having a perforated body, a wire passing through the body of the cup on line with the perforations, the portion of the wire inside the cup adapted to support a shaving brush, the end outside the cup being bent downwardly and sealed in place by a band pasted around the body of the cup 80 along the line of perforations.

85 In testimony whereof I affix my signature.

ABRAHAM J. EISENBERG.
